Otto F. Fogelstrand,
By James Shepard Ott,

UNITED STATES PATENT OFFICE.

OTTO F. FOGELSTRAND, OF KENSINGTON, CONNECTICUT, ASSIGNOR TO HART,
BLIVEN & MEAD MANUFACTURING COMPANY, OF SAME PLACE.

DESIGN FOR PAPER-WEIGHT.

Specification forming part of Design No. **7,248**, dated March 17, 1874; application filed March 7, 1874.
[Term of Patent 7 years]

To all whom it may concern:

Be it known that I, OTTO F. FOGELSTRAND, of Kensington, in the county of Hartford and State of Connecticut, have invented and produced a new and original Design for a Paper-Weight, of which the following is a specification:

The nature of my design is fully represented in the accompanying cut, to which reference is made.

A represents the handle, which is capped by raised ornaments somewhat resembling the calyx of a flower. Oval ornaments are on the periphery of the handle, and its stem is fluted. B represents the weight proper, and it is eight square at the bottom and square at the top. Four of the sides form triangular figures, the

sharp point of each triangle meeting the corner of the square top. Each of the sides are bordered by a raised ledge, within which is ornamental work in relief. The handle is mounted upon the top of the weight B at its center.

I claim as my invention—

A design for a paper-weight, in which the weight proper is composed of an eight-sided base, eight tapering sides, a square top, and a handle, all ornamented in the manner substantially as shown and described.

OTTO F. FOGELSTRAND.
